UNITED STATES PATENT OFFICE.

CHARLES HANSON RAYNER, OF ST. JOHNS, QUEBEC, CANADA.

COMPOSITE WATERPROOF SHEET AND PROCESS OF MAKING THE SAME.

Application filed January 28, 1927. Serial No. 164,264.

The invention relates to composite waterproof sheets, and the process of making the same, as described in the present specification and illustrated in the accompanying drawings that form part of the same.

The invention consists essentially of the novel features of construction pointed out broadly and specifically in the claims for novelty following a description in detail of an acceptable form of the invention.

The objects of the invention are to furnish interlining means for the insulating walls of an enclosure in order to maintain the atmosphere of the interior in an equable condition; to construct an insulation sheet that will permit a limited aeration and thereby avoid the deadness incidental to the use of close grained or pressed fillers; to eliminate the retention of hot or cold air or moisture for a considerable period, and in place promote a continuous ventilation through the looseness of the filler material, and to provide an effective covering for various uses that will prove cheap to produce and durable.

In the drawings, Figure 1 is an outline view showing diagrammatically the manner employed for interlocking the gauze and felt with a backing.

Figure 2 is a diagrammatic view, showing the means employed for making the artificial leather.

Figure 3 is an enlarged sectional detail showing the gauze reinforcing the felt for the composite sheet.

Figure 4 is a sectional detail showing the interstrung as the reinforced sheet.

Like numerals of reference indicate corresponding parts in the various figures.

Referring to the drawings, the binding sheet 10 is a composite sheet comprising paper and a reinforcing gauze held together by a strong adhesive. Felt paper, such as building paper may be used if desired with an open mesh textile as the reinforcement, though a paper reinforced with string is excellent for the purpose.

The felt paper is indicated by the numeral 11 and the string paper is indicated by numeral 12 and the gauze by 16.

The binding sheet 10 may be soaked in a fire proof compound, such as stannic chloride. The loose hair of fibrous material is gathered together through the machine 13

and made into a loose bat, being held together by capillary attraction and forming a layer of loose hair clinging together and laid on a sheet of paper reinforced by a textile fabric or string. This sheet with the hair is passed through the needle loom 14, which has the barb points 15, operating reciprocally and carrying the hair ends through the reinforced sheet and locking the hair thereto.

In making artificial leather from this filler, the hair is interlocked with the reinforced sheet and the hairs through the back singed, that is to say, the filler is passed under a hot roller that will singe all the free hairs on the back surface of the reinforced sheet thereby smoothing said surface in preparation for an asphalt adhesive.

The integral base or binding sheet is now pressed so that all the holes in the filler are closed by the water proof substance, and furthermore all unevenness smoothed out, and in this condition, the filler is ready for the collodion or other compound used in making the coating for artificial leather, which is applied in the usual manner by putting on a number of coats though it may be covered by the rubbered cloth 17 or other ornamental sheet suitable for the purpose.

What I claim is:

1. The herein described method of producing a composite waterproofing sheet consisting in soaking the reinforced paper in stannic acid laying loose strands of hairy material on a sheet of reinforced paper, breaking irregular holes in the paper and carrying hair therethrough singeing the hair projecting through on to the back of the sheet, laying asphaltum over the surface of the singed back and laying collodion over the asphalt surface.

2. A composite waterproofing sheet comprising a reinforced paper backing interlaid with string, a filler formed of loose strands of hairy material penetrating the backing at many places and adhering thereto, a coating of asphaltum covering said backing, and a layer of collodion forming a surfacing over the asphaltum of imitation leather.

Signed at Montreal, Canada, this 18th day of October, 1926.

CHARLES HANSON RAYNER.
